UNITED STATES PATENT OFFICE.

JACOB BILLER, OF NEW YORK, N. Y.

DESIGN FOR A BELT.

SPECIFICATION forming part of Design No. 26,878, dated April 13, 1897.

Application filed February 6, 1897. Serial No. 622,865. Term of patent 7 years.

To all whom it may concern:

Be it known that I, JACOB BILLER, of New York city, in the county and State of New York, have invented and produced a new and original Design for a Belt, of which the following is a full, clear, and exact description.

Reference is to be had to the accompanying drawings, forming a part of this specification, in which similar characters of reference indicate corresponding parts in all the figures.

Figure 1 is a side elevation of a belt embodying my design. Fig. 2 is a front elevation, and Fig. 3 is a plan view of the belt.

The leading feature of my design consists in a waist-belt the opposite edges of the body of which present sinuous lines lengthwise of the belt, the sinuations of the opposite edges having a similar trend.

Another feature of my design consists in a rosette-like projection on the belt, having a

curved line across its center and a button-like figure at its center.

Referring particularly to the drawings, the belt has its side portions elevated, as at 1, 25 and its front and rear depressed, as at 2. At the front of the belt is a buckle-like structure 3 and a transverse strip 4.

On the belt is a round rosette-like projection 5, having a curved line 6 across its center, giving it the appearance of being in two parts, and at the center is a button-like figure 7. The rosette-like portion is frustoconical and at its top a slot-like opening is represented. 35

I claim—

The design for a belt, substantially as shown and described.

JACOB BILLER.
